UNITED STATES PATENT OFFICE.

ARTHUR GEORGE LLOYD NEIGHBOUR, OF BRIGHTON, VICTORIA, AUSTRALIA.

MAGNETO-ELECTRIC IGNITION MACHINE.

Application filed August 15, 1922. Serial No. 582,073.

To all whom it may concern:

Be it known that I, ARTHUR GEORGE LLOYD NEIGHBOUR, a subject of the King of Great Britain, residing at 1 Oak Grove, Brighton, in the State of Victoria, Commonwealth of Australia, have invented certain new and useful Improvements in or Relating to Magneto-Electric Ignition Machines; and I do hereby declare the following to be 10 a full, clear, and exact description of the invention, such as will enable others skilled in the art to which it appertains to make and use the same.

This invention relates to magneto electric machines, ordinarily termed magnetos, which generate currents that periodically reverse in direction and increase in strength from zero to maximum values.

Magnetos having these characteristics are 20 commonly employed for ignition purposes in internal combustion engines. In the more frequently employed type of machine known as a "two-spark" magneto, the current undergoes one complete reversal or 25 cycle during each revolution of the armature, and attains two maximum values which may be used to furnish two sparks. Other machines are designed to have two complete cycles per revolution with corresponding production of four sparks.

It is an object of this invention to provide a magneto of simple construction having an armature of special form and arrangement which may be designed to furnish as many 35 sparks per revolution as there are ignition periods in one complete working cycle of the engine to which it is to be applied.

For example a six cylinder engine completes one cycle of work in two revolutions 40 during which there are six impulses which require six ignitions. The magneto when employed on such an engine may be constructed to yield six sparks per armature revolution and as these sparks are required 45 at equal intervals during two revolutions of the engine it will be obvious that the magneto will require to be driven at one half the speed of the crank shaft that is at the speed of the engine cam shaft. This renders 50 the magneto of special value in its application to high speed multi-cylinder engines as by its reduced speed the rate of wear is diminished and the risk of break-down minimized.

Owing to the production during one revolu-

tion of the armature of all the sparks required in one complete working cycle of the engine, it will further be obvious that the rotating element of the distributor may revolve at the same speed as the armature. 60 Advantage is taken of this to mount the rotating distributing element or distributor rotor on the armature itself, and to arrange the stationary portion of the distributor, herein-after termed the distributor stator concentrically about the axis of rotation. In this manner the construction is greatly simplified as the usual slip ring and high tension collecting and conducting devices may be eliminated. Moreover, the distributor shaft 70 with its bearing, actuating gears, and auxiliary parts, ordinarily fitted in a multi-cylinder magneto may be dispensed with.

A salient feature of this invention resides in the provision of an armature having an 75 inner core of magnetic material of high permeability, an outer core of non-magnetic material accommodating the armature winding, radial slots formed in the ends of the outer core, and inductors of highly permeable 80 magnetic material fitting the radial slots and magnetically associated with the inner core. The inner core and inductors can be made of unitary construction, and can consist of an assemblage of suitably formed 85 laminations or stampings of highly permeable magnetic material. These laminations have centrally disposed axial portions and lateral extensions corresponding to the inner core and inductors respectively. The armature core constructed in this manner is mounted in jaws or lugs formed on end plates, and in the space between the conductors the armature windings are located. The armature is mounted in a magneto in such 90 manner that the axis of the inner core coincides with the axis of rotation around which the inductors are radially disposed.

During rotation of the armature in a suitable transversely disposed magnetic field, 100 cyclical flux changes are brought about in the inner core by the radial inductors. The magnetic flux is by means of said inductors diverted through the inner core and then provided with a path of lower reluctance 105 across the ends of the core, then again diverted in an opposite direction through the inner core, and again given a path of less reluctance across the ends of the core and so on, these changes occurring in a definite 110

order or cycle. In this manner a magnetic field is alternately created and collapsed through the armature windings thereby effecting the generation of alternating currents having periodical maximum values.

The radial inductors may be sufficient in number and spaced at required intervals to bring about as many maximum current values per revolution of the armature as there are ignitions in a complete cycle of work in a given type of engine. Accordingly these radial inductors may be arranged to suit the ignition periods of engines having one, or more cylinders. Moreover, by suitable design of the pole pieces and arrangement of the radial inductors, magnetos may be constructed to suit the ignition periods of V type or other engines.

Another object of the invention is to provide a simple unitary type of framing which can be constructed as a casting, and on which the various operative and co-acting parts are secured or mounted. This framing is preferably constructed as a sleeve which is detachably mounted in the housing or body casting of the magneto, and may readily be removed therefrom for inspection or repair. In the event of breakdown, the sleeve may be quickly replaced by another having mounted thereon a complete assemblage of duplicate parts in good order and adjustment. Auxiliary pole pieces are fixed to this sleeve in addition to main pole pieces mounted in said housing or body casting. Timing is effected by rotating the sleeve on its axis and with it the auxiliary pole pieces. The armature accordingly always bears a definite relationship to the auxiliary pole pieces when the primary circuit is interrupted, the current at any given speed will remain constant and the intensity of the spark will be the same for all adjustments of the timing.

Further objects of the invention consist in the provision of means enabling the magneto to operate in either direction of rotation without structural alteration; an interrupter or contact breaker of simple construction which will function efficiently in either direction of rotation; and means for housing the condenser in the armature in such a manner that it may readily be removed and replaced without disturbing other parts of the latter.

Reference being had to the drawings illustrating the invention:

Figure 1 is a view in longitudinal vertical section of a "six-spark" magneto.

Figure 2 is a view in transverse section on the line 2--2 in Figure 1.

Figure 3 is a view in elevation at the end of Figure 1 whereat the contact breaker is located, the cover of the latter being removed for clearness of illustration.

Figure 4 is a view in perspective of the armature illustrated in Figure 1, shown detached and without windings.

Figure 5 is a view in perspective of a "two-spark" unwound armature.

Figure 6 is a view in perspective of a "four-spark" armature without windings.

Figure 7 is a view partly in side elevation and partly in section of a detail of the invention.

Figures 8 and 9 are diagrammatical views illustrating the actions of a "four-spark" magneto.

Figure 10 is a view in end elevation of a modified detail of the invention.

Figure 11 is a view partly in section on the line II--II in Figure 10.

In these drawings the numeral 12 designates the housing or body casting of a magneto having secured thereto field magnets 13 which contact with fixed pole pieces 14 mounted in the housing 12. The magnets 13 are conveniently fixed to lugs 15 formed integrally with the housing 12 by screws as shown, and they may either contact with the sides of the fixed pole pieces 14 in the ordinary way, or rest upon the upper surfaces of the latter as illustrated in Figures 2, 8, and 9. Alternately the magnets 13 may be maintained in position by a cover 16 or band of sheet metal fixed by screws 17 to the housing 12.

The housing 12 is provided with flanged ends 18 which are, preferably, of equal thickness and similar in external configuration, and the interior of said housing is accurately bored to form a cylindrical chamber 19 open at both ends.

In the chamber 19 is rotatably fitted a cylindrical sleeve 20 which is clearly illustrated in Figure 7. This sleeve 20 is constructed of non-magnetic metal and is furnished with an enlarged extension 21 forming a shoulder 22 which bears against a flanged end 18 of the housing 12. The sleeve 20 may be inserted into either end of said housing and said sleeve is retained in position by the shoulder 22 and a collar 23 which may be screwed upon its opposite end or fixed thereto as by screws 24. In some cases in which the enlarged extension 21 is not required a collar as 23 may be provided at both ends of the sleeve 20.

In the sides of the sleeve 20 are mounted auxiliary pole pieces 25, hereinafter referred to as movable pole pieces, which are constructed to be closely contiguous to said fixed pole pieces 14. These pole pieces 25 can be solidly constructed, but are preferably, of laminated structure and fixed in the sleeve 20 by die-casting.

The sleeve 20 is provided with an inwardly projecting flange 26, and the enlarged extension 21 of said sleeve is furnished with a cover or diaphragm 27. This cover 27 is

spigoted to the extension 21 and said cover is fixed thereto by screws 28 which are passed into lugs 29, preferably, formed on the inner side of said extension. In flange

5 26 and cover 27 are respectively mounted bearings 30 and 31 which rotatably support the armature of the magneto.

A casting 32 of non-magnetic metal forms the primary unit or element to or on which 10 the component parts of the armature are secured or mounted. This casting which is shown more clearly in Figure 4 comprises a central axial drum or barrel 33 which is bounded at its opposite ends by circular 15 cheeks 34.

In the space between the cheeks 34 the primary and secondary windings of the armature are located, said axial drum 33 and cheeks 34 forming a spool or reel upon and 20 around which said windings are peripherally wound. The primary and secondary windings are indicated by numbers 35 and 36 respectively, and these windings are insulated and electrically associated in the 25 usual manner.

On the outer side of each cheek 34 and formed integrally therewith are lugs 37 which are spaced at equal angular intervals apart, the lugs 37 on one cheek being positioned in such manner that they bisect the angles between said lugs on the opposite cheek as clearly indicated in Figures 2 and 4.

The interior of the casting 32 is axially bored to receive a tube 38 of magnetic material, preferably soft iron, which projects beyond the lugs 37 and forms spigots 39 upon which parts of the armature hereinafter described are mounted. This tube 38 is packed with soft iron wires 40, in manner commonly 40 adopted in the construction of induction coils in order to restrict the flow of eddy currents.

The lugs 37 are slotted radially to accommodate inductors 41 which preferably 45 comprise assemblages of stamped laminations of soft iron which are conveniently secured in place by transverse rivets 42. The laminated inductors 41 at their inner ends contact closely with the iron tube 38, and in 50 order to effect a close union therewith they are fixed in lugs 37 prior to the boring of the casting 32.

The casting 32 is preferably manufactured by the process of die-casting, the laminated inductors 41 being cast in position.

The condenser 43 is, preferably, arranged at the driven end of the armature and is positioned in a diametrically disposed chamber 44 formed in a housing 45. This housing 45 60 is mounted on a spigot 39, and is retained in position by screws 46 which are passed into longitudinal bosses 47 formed between each of the lugs 37. Holes 46 are made in the opposite side of the housing 45 to permit of 65 the insertion and withdrawal of the screws

46. The condenser 43 is associated with the outer end of the primary winding by a conductor 48, and is connected in parallel with the contact breaker in the ordinary way.

The driving shaft of the magneto is secured to the condenser housing 45 in the usual manner and this shaft extends outwardly from bearing 30.

Mounted on the spigot 39 at the opposite end of the armature is the flanged end 50 of the contact breaker shaft 51. This shaft 51 is fixed to the armature casting 32 in a similar manner to the condenser housing 45, namely by screws 46 which are passed into the bosses 47. The shaft 51 is supported by 70 and extends through the bearing 31 and at its end said shaft is tapered to fit the base plate 52 of the contact breaker hereinafter described.

Mounted on the contact breaker shaft 51 80 and secured to the flanged end 50 thereof by screws 53 is the distributor rotor 54. This rotor 54 is constructed of insulating material and carried a metal brush 55 which is, preferably, moulded into it. This brush 90 is connected to the end of the secondary winding 36 by an insulated conductor 56.

The distributor is preferably of the "spark gap" type in which a rotary brush moves past a series of stationary collectors 95 and is separated from the latter by a short interval or gap, across which the high tension current leaps to each collector in succession.

In the distributor illustrated in Figures 1 100 and 3, six equally spaced terminals 57 of insulating material are concentrically arranged about the axis of rotation and around the contact breaker hereinafter described.

The terminals 57 are supported at their 105 inner and outer ends in accurately aligned holes 58 and 59 formed respectively in the cover 27 and in a metal cap 60 which is mounted on a spigot 61 formed on said cover. The cap 60 may be secured in place by 110 screws (not shown) which are tapped into the cover 27, but said cap is preferably fixed in position by the screws 28, which are made of sufficient length to pass through both the cap 60 and the cover 27.

A metal stem 62 is moulded in each terminal 57 and projects from each end thereof. The inner ends of the stems 62 function to collect current from the rotary brush 55 and the outer ends of said stems are threaded 120 to receive terminal nuts 63 preferably furnished with heads of insulating material.

A boss 64 is formed on the sleeve 20, and is furnished with a window 65 to enable the brush 55 to be seen to facilitate the timing of 125 the magneto when the same is being mounted on an engine.

The contact breaker base plate 52 previously referred to is secured to the contact breaker shaft 51 in the usual manner to a 130

central screw 66 which bears upon and passes through an insulated metal block 67 mounted on the base plate 52. This screw 66 is axially disposed within and insulated from the 5 contact breaker shaft 51, and at its inner end said screw engages with a fixed insulated nut 68. This nut 68 is prevented from rotating by a diametrically disposed pin 69 with which it engages. This pin extends 10 through insulating bushes 70 in the flanged end 50 of the contact breaker shaft 51. At one end the pin 69 is extended radially outwards and is connected to the end of the primary winding 35 by a conductor 71, shown 15 clearly in Figures 5 and 6.

The insulated metal block 67 is accordingly electrically connected with the outer end of the primary winding at all times. Said insulated block 67 is constructed with 20 the radial branches or extensions 72 which are disposed on opposite sides of a diametral plane with which said branches make equal angles.

Screws 73 are passed through and insulated 25 from the base plate 52, and these screws engage with tapped holes the branches 72 of the insulated block 67. By means of the screws 73 said insulated block is fixed securely to the base plate 52 even when the 30 central screw 66 is removed.

In said diametral plane and on the side of the axis of rotation remote from the branches 72 and at a required distance from said axis, is positioned a pivot or pin 74, 35 which is securely fixed in the base plate 52.

On the pivot or pin 74 is mounted a bush 75 of insulating material which forms a bearing for the contact breaker lever 76. This lever is of the usual bell crank construction having a fibre heel 77 at one end 40 and a contact 78, hereinafter referred to as the movable contact at the opposite end.

A co-operating contact 79 termed the insulated contact is mounted on a screw 80 45 which is adapted to fit threaded holes 81 in the branches 72. The screw 80 is capable of endwise adjustment and is provided with a lock nut 82 in the usual manner.

In said diametral plane, and formed integrally with the base plate 52 and positioned between the branches 72, is an outwardly projecting lug 83 to which is attached one 50 end of a spring 84 by a screw 85. The spring 84 at its opposite end is attached to said lever 76 by a screw 86. Said spring 84 functions in the usual manner to maintain the movable contact 78 upon the insulated 55 contact 79.

A hole is made through the boss of the 60 lever 76, and this hole is made of such diameter that it fits neatly the exterior of the bush 75. An insulating washer 88 is interposed between the lever 76 and the base plate 52.

65 A flat spring 89 bears upon the outer end

of the bush 75 and retains the latter and the lever 76 in place upon the pivot or pin 74. The central screw 66 passes through a hole made in the opposite end of the spring 89 and the latter is clamped between the head 70 of said screw and the insulated block 67, but not so tightly as to prevent its being turned aside when it is necessary to remove the lever 76.

The movable contact 78 is separated from 75 the insulated contact 79 in the usual manner, by impact of the fibre heel 77 with cams 90 fixed concentrically around the contact breaker.

The cams 90 can conveniently be constructed as sleeves preferably of hardened steel which are tightly fitted upon the outside of the terminals 57. These cams or sleeves 90 when unduly worn by the fibre heel 77 can be made to present unworn surfaces to the latter by slightly turning the terminals 57 on their axes. 85

The usual earthing brushes 91 indicated by broken lines in Figure 3 are provided at the back of the base plate 52.

A cover 92 preferably of insulating material is mounted on the cap 60 and is retained in position thereon by flat springs 93 fixed to said cap by rivets or the like.

A carbon earthing brush 94 is located 95 centrally in the cover 92, and bears upon the head of the central screw 66. The brush 94 is mounted in a metal holder moulded in the cover 92, and the outer end of this holder is threaded and is provided with a terminal nut 100 95 for connection with the usual earthing switch.

The contact breaker above described can be quickly adjusted to operate in either direction of rotation with equal efficiency.

It is imperative for efficient operation of a contact breaker that the fibre heel 77 should trail behind or follow the pivot 74 of the contact breaker lever 76 during rotation. If the fibre heel 77 leads or moves in advance 110 of the pivot 74, the former will wear and chattering of the lever will occur and undue wear of the bush 75 will result.

In Figure 3 the contact breaker is shown adjusted for operation in a clockwise or 115 right-handed direction when viewed as customary from the opposite end or driving end of the magneto.

The lever 76 having no lateral projections and being symmetrically supported on the 120 bush 75 may be removed from the pivot pin 74 and turned over so as to bring its respective arms into precisely similar positions on opposite sides of the diametral plane passing through the pivot pin 74 and the spring supporting lug 83, as clearly indicated by broken lines in Figure 3. The spring 84 is adjusted to extend from the opposite side of the lug 83, similarly shown by broken lines 125 in Figure 3, and the screw 80 bearing the 130

insulated contact 79 is transferred to the hole 81 in the other branch 72 of the insulated block 67.

It will be observed that the various parts 5 after reversal and transference, take up exactly similar positions on the opposite sides of the diametral plane mentioned above. After adjustment of the insulated contact 79 has been effected to give the required break or distance between the contacts 78 and 79 when separated, it will be found that the contact breaker will operate in the opposite direction of rotation with equal efficiency.

15 It will be obvious to persons skilled in the art that a contact breaker constructed in the manner above described has considerable advantages over the usual type of contact breaker, for in addition to the ease with 20 which it may be altered to operate in either direction, it simplifies manufacture in that only one contact breaker is required instead of two suited respectively to clockwise and anticlockwise directions of rotation.

25 As shown in Figures 1 and 2 the armature when placed in a magneto is arranged with its core co-axially disposed in relationship to the axis of rotation, the radial inductors 41 being adapted to rotate closely 30 past the movable pole-pieces 25.

The flux changes occurring in the armature core may be readily understood by reference to Figure 2, in which the direction of the magnetic field is indicated by arrows, 35 the right hand limb of the magnet being assumed to be a north pole as indicated by the letter N. In the position illustrated the magnetic flux passes as indicated by arrows through the inductors 41 and across the 40 end of the armature core, but not in an axial direction through the latter.

This is the position of zero flux in the core and approximately peak voltage in the armature windings, and is approximately 45 the position in which the contacts 78 and 79 should separate as shown in Figure 3, and in which the distributor brush 55 should face one of the terminals 57 as shown in Figures 1 and 3.

50 Upon further movement of the armature in the direction of the arrow shown in Figures 2 and 3, the magnetic flux will change its position passing in through the inductor 41 facing the north pole down through the 55 armature core in a direction away from the observer and out through the opposed inductor 41 facing the opposite pole and at the opposite end of the armature, as shown by broken lines. When the opposed inductors 60 41 take up a horizontal position in extended alignment from pole to pole, the flux in the armature core will be a maximum and the current in the windings zero.

65 After still further movement of the armature the flux will again change its position

and pass across the ends of the core, and a second position of peak voltage or maximum current and zero flux will be attained. This position of peak voltage synchronizes with the arrival of the fibre heel 77 at the next 70 cam 90 and the brush 55 at the next terminal 57.

Upon continuance of the motion of the armature the flux will again be diverted through the armature core in an opposite 75 direction, on this occasion towards the observer, and another position of zero current and maximum flux will be reached. This will be followed by a position of maximum current and zero flux, and so on, the flux 80 changes occurring to a definite order or cycle.

Each position of the armature to which the current attains a maximum value, synchronizes with the contact of the fibre heel 77 with a cam 90 and the arrival of the brush 85 55 at a terminal 57.

Further consideration will show that with the arrangement of inductors illustrated in Figures 2 and 4, six peak voltage maximum current positions will be obtained in each 90 revolution of the armature with accordingly the production of six sparks.

Inspection of Figures 2 and 3 will show that alteration and adjustment of the contact breaker as previously described is all 95 that is necessary to enable the magneto to function when driven in its opposite direction of rotation. When lever 76 is reversed as indicated by broken lines the fibre heel 77 will contact with the corresponding cam 90 100 on the opposite side of said diametral plane. The contacts 78 and 79 will accordingly be separated and the brush 55 will still face the lowest terminal 57.

If the armature be now rotated in the opposite or anticlockwise direction, the magnetic flux will pass from the north pole into the inductor 41 at the further end of the armature and will extend up the core towards the observer and out through the inductor 41 facing the opposite pole at the nearer end of the armature. Upon continuance of the action of the armature a position of maximum flux will be attained which will later be followed by a position of maximum current which latter synchronizes with the arrival of fibre heel 77 at the succeeding cam 90 and the brush 55 at the next terminal 57.

Advance and retard timing movements are 120 effected by rotating the sleeve 20 on its axis by means of a timing lever 96. The advance and retard movements are conveniently limited by a pin 97 which is fixed in the housing 12, and projects into a slot 98 125 formed in the collar 23.

During the timing range of movement of the sleeve 20, the movable pole pieces 25, cams 90, and distributor terminals 57 being rigidly fixed to said sleeve are always kept 130

in the same relative positions. Accordingly for all positions of the timing lever 96 and sleeve 20, the fibre heel 77 will always contact with the cams 90 when the radial inductors 41 are in the maximum current position relative to the movable pole pieces 25, so that for any given speed, the current when the contacts 78 and 79 are separated will be constant and the maximum obtainable at that speed, and the intensity of the spark will be the same for all positions in the timing range.

In this manner one of the inherent defects of the high tension magneto is obviated.

In magnetos as ordinarily constructed with fixed pole pieces, the maximum current in the windings at any given speed will occur when the armature occupies a definite position in relationship to the pole pieces. It is customary to construct the contact breaker in such manner that when fully advanced the separation of the contacts coincides with the maximum current position of the armature. If the separation of the contacts be retarded the armature will have moved away from the maximum current position, and the current interrupted will be of lower value and the intensity of the spark will be proportionately reduced. This is most marked at starting and at low speeds when it is necessary to retard the ignition, the intensity of the spark being greatly reduced.

In multi cylinder magnetos wherein a distributor mounted on a separate shaft driven by gearing from the armature shaft is employed, the stator takes no part in the timing adjustments. Ordinarily the contacts close when the timing lever is fully advanced, immediately before the distributing brush leaves a distributor collector, consequently when fully retarded the distributing brush will have moved away from the collector when the contacts close. At high speeds the high tension current is not extinguished until the contacts close again, so that sparking is apt to occur between the brush and the collector which will burn the insulation, especially when a carbon brush distributor is employed.

This is recognized as another inherent defect of the high tension magneto, which is obviated in this invention by mounting the distributor stator upon the movable sleeve 20 so that the brush 55 always faces the terminals 57 in all positions of the timing.

By releasing the collar 23 on the sleeve 20 and disconnecting the shaft 49 from the driving shaft as coupling on an engine, the sleeve 20 and all the operative parts mounted thereon can be withdrawn from the housing 12 without removal of the latter from the engine. The sleeve 20 and all the parts thereon may be readily inspected and re-

pairs effected if necessary. Said sleeve 20 may also have another substituted for it having all parts in good order and adjustment. All parts being similar and occupying the same relative positions the timing in the relationship to the engine will be correct when the shaft 49 on the substituted sleeve 20 is connected to the driving shaft or coupling on the engine.

In Figures 5 and 6 are shown armature constructions in which the drum or barrel 33 and radial inductors 41 are comprised of assemblages of one-piece laminations or stampings of soft iron having high permeability.

In the case of the two-spark armature shown in Figure 5, the laminations are made of approximately Z-shaped outline, and they are assembled by one or more rivets 99. When the laminations are assembled in this manner an inner core 100 is formed, upon and around which the armature windings 35 and 36 are wound.

At each end of the inner core 100 and likewise formed by the assemblage of said laminations is located a radial inductor 41. Said opposed inductors are co-planar, but are arranged in extended diametrical alignment.

The completed armature core, comprising the inner core 100 and opposed inductors 41, is mounted in lugs or jaws 101, and secured therein by transverse rivets 102.

The lugs or jaws 101 at one end of the armature core are formed integrally with a condenser housing 103, having therein a condenser chamber 44 and a driving shaft 49 attached thereto as previously described.

The lugs or jaws 101 at the opposite end of the said armature core are formed integrally with an end plate 104, which has concentrically formed thereon a boss 105, into which is spigoted the flanged end 50 of the contact breaker shaft 51. This shaft is secured to the boss 105 by screws 53^a previously mentioned. Discs 106 made of insulating material and in halves, are positioned at each end of the inner core 100. The discs 106 are secured in place by screws 107 which are passed there-through and into threaded holes in bosses 108 formed on the sides of said lugs 101. Said discs may further be secured by extensions 109 of the inductors 41 which project across their peripheries as shown in Figures 5 and 6.

These discs 106 and the inner core 100 form a spool or reel as previously described, on which the armature windings are wound.

The two-spark armature just described is located in the sleeve 20 between oppositely disposed movable pole-pieces 25, and as it rotates the magnetic flux is alternately diverted through the core and transversely across the ends thereof in the manner previously described, two peaks or maximum

current positions being attained during each revolution.

In the four-spark armature shown in Figure 6, the armature core is made up of 5 an assemblage of I-shaped laminations or stampings which are secured together by rivets 110. The assemblage of laminations is held in suitable dies and twisted to bring the inductors 41 at opposite ends thereof 10 into planes disposed at right angles to each other, the inductors 41 at each end of the armature being in diametrical alignment.

The armature core so constructed is mounted and secured in lugs or jaws 101 by rivets 102. Said lugs or jaws 101 being 15 formed respectively on a condenser housing 103 and an end plate 104 as described above.

Discs 106 of insulating material are mounted at opposite ends of the inner core 20 100 and are fixed in position by screws 107, in precisely the same way as in the above described two-spark armature.

In the case of a four-spark armature it is necessary that the movable pole pieces 25 26 should be positioned approximately at right angles to each other as shown in Figures 8 and 9.

In Figure 8 the armature is shown in a 30 position of zero flux and approximately peak voltage. The flux passes longitudinally through the near inductors 41, and transversely across an end of one of the remote inductors as indicated by the arrows in Figure 8, and not through the axial inner core 100.

In Figure 9 the armature has moved into a 35 position of approximately maximum flux and zero current. In this position the magnetic flux passes inwards through one of the 40 near inductors 41, down the inner core 100 and out through one of the further inductors 41.

After further movement of the armature has taken place another position of zero flux 45 and maximum current will be reached, in which the magnetic flux will extend transversely across the end of one of the near inductors 41 and longitudinally through the remote inductors 41.

This will be followed by a position of 50 maximum flux and zero current in which the flux passes inwardly through a remote inductor 41 up through the core towards the observer and out to the opposite pole 55 through a near inductor 41. After further movement the inductors will again occupy a similar position to that illustrated in Figure 8, and the cycle of flux changes will be repeated.

Consideration will show that four maximum current values will be attained during each revolution of the armature, corresponding to the production of four-sparks.

In Figures 10 and 11, are illustrated a 60 modified and preferred distributor structure

arranged for a four-spark magneto, and a modified detail of the contact breaker previously described. These are shown mounted upon the enlarged extension 21 of the sleeve 20, which is broken away for convenience of illustration.

The cover 27 is provided with a concentric extension which forms the housing or cam cage 111 of the contact breaker. Upon the housing 111 is mounted an annular distributor stator 112, constructed of insulating material, preferably by moulding.

The stator 112 is of the "flush" type, having metal terminals 113 moulded therein and cable sockets 114 into which the ends of the 80 high tension cables are inserted and secured by pointed screws 115.

Formed integrally with the stator 112 are a series of nipples 116, which extend through holes 58 in the cover 27. Axially positioned 85 in said nipples 116, are metal collecting stems 62 which are screwed into the terminals 113.

In place of the separate sleeve cams 90 previously described, a cam ring 117 having 90 cams 118 formed integrally therewith, is mounted within the housing or cam cage 111.

A cover 92 of insulating material is mounted on the end of the housing 111 and 95 is retained thereon by a flat spring 119 which is mounted on a pillar 120 fixed in a lug 121 formed on said enlarged extension 21.

The cover 92 is provided with an earthing switch brush 122 of usual construction, and 100 a pointed screw terminal 123 moulded therein, for connection with the earthing switch cable.

Preferably, the cover 92 and the annular distributor 112 are formed integrally together as a single moulding as shown by 105 broken lines in Figure 11.

The distributors herein described and illustrated are of spark gap construction, but if required carbon brush distributors 110 may be employed in lieu thereof.

I claim:

1. A magneto of the rotary armature type having a body casting provided with field magnets and fixed pole pieces, an oscillatable sleeve of non-magnetic material passing through and having its ends projecting beyond the body casting, means for retaining the sleeve within the body casting, auxiliary pole pieces in the sleeve magnetically associated with pole pieces in the body casting, a bearing in one end of the sleeve, an enlarged extension on the opposite end of the sleeve, a cover on the enlarged extension, a bearing in the cover, an armature having 115 end shafts rotatably supported in the bearings, an axial core on the centre of the armature, radial jaws at the ends of the core, inductors in the jaws at the ends of the core, annular discs on the ends of the core adja- 120 125 130

cent to the inner faces of the radial inductors, primary and secondary windings peripherally disposed on the core of the armature, a distributor rotor on the armature, a 5 distributor stator on the cover, a plurality of collectors arranged symmetrically around the axis of the distributor stator, terminals, associated with the collectors, a contact breaker located concentrically within the 10 distributor stator, a timing lever on the sleeve, a condenser housing on the driving end of the armature, and a condenser in said housing.

2. In a magneto of the rotary armature 15 type, an armature provided with an inner axial core of high magnetic permeability, an outer core of non-magnetic material, windings peripherally wound on and about the outer core, radially disposed jaws at the 20 ends of the outer core, and radial inductors of highly permeable magnetic material in said jaws and magnetically associated with the inner core.

3. In a magneto of the rotary armature 25 type, an armature having an inner axially disposed core of high magnetic permeability, an outer core of non-magnetic material, cheeks at the opposite ends of the outer core, primary and secondary windings peripherally wound on the outer core and positioned 30 between the cheeks, jaws on said cheeks, radial inductors in said jaws and magnetically associated with the inner core, a condenser housing fixed to one end of the outer core, a 35 driving shaft fixed to the condenser housing, a contact breaker shaft fixed to the opposite end of the outer core, and a distributor rotor fixed to the contact breaker shaft.

4. In a magneto of the rotary armature 40 type having a body casting provided with field magnets and fixed pole pieces, an oscillatable sleeve passing through the body casting, a removable locking ring for retaining 45 the sleeve within the body casting, auxiliary pole pieces in the sides of the sleeve, an armature rotatively supported within the sleeve, an axially disposed core of high magnetic permeability on the armature, an outer 50 core of non-magnetic material, primary and secondary windings disposed peripherally on the outer core, radially disposed jaws at the ends of the outer core, radial inductors of highly permeable magnetic material in 55 said jaws and magnetically associated with the inner core, a distributor rotor fitted to one end of the armature, a brush on the distributor rotor, a distributor stator having a 60 fixed relationship and disposed concentrically to the sleeve and collectors on the distributor stator adjacent to the path of the brush and corresponding in number to the total number of radial inductors on the armature.

5. In a magneto of the rotary armature

type, an armature having an axially disposed core and radial inductors formed of an assemblage of one piece laminations, a condenser housing at one end of the core, an end plate at the opposite end of said core, 70 jaws on the condenser housing and on the end plate forming mountings for said core and inductors, discs of insulating material fixed to the jaws, and primary and secondary windings peripherally disposed on said 75 core between said discs.

6. A magneto of the rotary armature type having a body casting provided with field 80 magnets and fixed pole pieces, an oscillatable sleeve passing longitudinally through the body casting, auxiliary pole pieces in the sides of the sleeve, bearings disposed co-axially with the sleeve, an armature provided with an axially disposed core and rotatively supported in the bearings, primary and secondary windings on the core, radial inductors on 85 the core, a condenser at one end of the armature, a contact breaker shaft fixed to the opposite end of the armature a contact breaker mounted on said shaft, a distributor stator 90 concentrically disposed about the contact breaker and oscillatable with the sleeve, and a distributor rotor on the armature between the contact breaker and the inductors on the adjacent end of the core.

7. A magneto having an armature provided with an axially disposed core, primary and secondary windings wound on the core, radial inductors on the core, a condenser on one end of the armature, a contact 100 breaker shaft fixed to the opposite end of the armature, a contact breaker mounted on said shaft, a distributor stator concentrically disposed about the contact breaker, and a distributor rotor on the armature between 105 the contact breaker and the adjacent end of the core.

8. In a magneto of the rotary armature type having a frame supporting field magnets and fixed pole pieces, a sleeve of non-magnetic material detachably mounted and rotatively adjustable in the frame, auxiliary pole pieces in the sides of the sleeve, an enlarged extension on one end of the sleeve, a 110 retaining ring removably fitted to the opposite end of the sleeve, an armature rotatively mounted within the sleeve, primary and secondary windings on the armature, a distributor rotor fitted to the armature and disposed within the enlarged end of the sleeve, 115 said rotor being associated with the secondary winding, and a distributor stator disposed concentrically with the distributor rotor and having a fixed relationship with the oscillatable sleeve.

9. In a magneto of the rotary armature type having a body casting provided with field magnets and fixed pole pieces, an oscillatable sleeve passing longitudinally through the body casting, auxiliary pole 120

pieces in the sleeve disposed in planes at right angles to each other, bearings disposed in axial alignment with the sleeve, an armature supported by the bearings rotatively within the sleeve, an axial core in the centre of the armature, diametrically opposed radial inductors at the ends of the axial core the inductors at one end being at right angles to the inductors at the other end of the core, primary and secondary windings on said axial core, a distributor rotor fitted to one end of the armature, a brush on the distributor rotor, a distributor stator having a fixed relationship with and disposed concentrically to the sleeve, and collectors on the distributor stator.

10. In a magneto of the rotary armature type, a frame having field magnets and fixed pole pieces, a sleeve supported within the body casting and adapted to partially rotate to effect timing adjustments, auxiliary pole pieces in the sides of the sleeve, an armature rotatively supported within the sleeve, an insulated brush on the armature, a contact breaker, contacts on the contact breaker, a distributor stator mounted concentrically with the sleeve and surrounding the contact breaker, distributor collectors in the said distributor stator, and cams disposed concentrically within the said distributor stator constructed and arranged whereby said sleeve will maintain the operative parts associated therewith in definite relationship and ensure that when the contacts are separated by said cams, the armature will occupy an approximately peak voltage position relative to the pole pieces and the distributor brush will evenly face the distributor collectors in all positions of the timing range.

40. 11. In a magneto of the rotary armature type having a body casting provided with field magnets and fixed pole pieces, an oscillatable sleeve passing through the body casting, an armature supported rotatively within the sleeve, an axial core on the armature, radial inductors on the end of the axial core arranged in pairs, the inductors of each pair being disposed in diametrical alignment on opposite ends of the core, a distributor rotor on the armature, and a distributor stator having a number of collectors arranged symmetrically around the axis of the armature and oscillatable with the sleeve.

55. 12. In a magneto of the rotary armature type having a body casting provided with the field magnets and fixed pole pieces, an oscillatable sleeve, of non-magnetic material passing through the body casting, auxiliary pole pieces in the sides of the sleeve, an armature having an axial core, primary and secondary windings wound on the core, radially disposed jaws at the ends of the core, a plurality of radial inductors in said jaws arranged in pairs on opposite sides of the windings and magnetically associated with

the core, a distributor rotor on the armature, a brush on the distributor rotor, a distributor stator disposed concentrically with the sleeve and having a fixed relationship therewith, and a plurality of collectors on the distributor stator disposed adjacent to the path of the brush on the distributor rotor whereby when the sleeve is oscillated a synchronous adjustment of the auxiliary pole pieces and the collectors is effected.

13. In a magneto of the rotary armature type having a body casting provided with field magnets and fixed pole pieces, a sleeve of non-magnetic material detachably mounted and rotatively adjustable in the body casting, auxiliary pole pieces in the sides of the sleeve, a locking ring for retaining the sleeve within the body casting, an armature axially positioned in the detachable sleeve, a driving shaft at one end of the armature, a co-axially aligned contact breaker shaft at the opposite end of the armature, an inwardly extending flange on one end of the sleeve, a cover attached to the opposite end of the sleeve, a bearing in the flange for the driving shaft, a bearing in the cover for the contact breaker shaft, a condenser mounted on the end of the armature provided with the driving shaft, a distributor rotor mounted on the end of the armature provided with the contact breaker shaft, and a distributor stator on the cover and arranged concentrically with the distributor rotor and having a fixed relationship with the oscillatable sleeve.

14. In a magneto as claimed in claim 13 a cap on the outer side of said cover, a series of concentrically arranged co-axially aligned and evenly spaced holes formed in the cover and in said cap, distributor terminals in said holes, collectors on the distributor terminals, an insulated brush mounted on the distributor rotor, and contact breaker cams on said terminals.

15. In a magneto as claimed in claim 13 a concentric extension on said cover forming a contact breaker housing, an annular distributor stator mounted on the contact breaker housing, symmetrically arranged evenly spaced holes in said cover, nipples formed on the annular stator corresponding in number to said holes and extending inwardly therethrough, terminals in said stator, collectors fixed in the terminals and extended through the said nipples, a cam ring in said contact breaker housing, a cover on said housing, and a spring maintaining said stator and cover in position.

16. A magneto as set forth and claimed in claim 15 having the distributor stator and contact breaker cover integrally united and constructed of moulded insulating material.

17. A magneto of the rotary armature type having a body casting provided with

field magnets and fixed pole pieces, an oscillatable sleeve of non-magnetic material passing through the body casting, auxiliary pole pieces in the sides of the sleeve, an 5 armature provided with an axially disposed core supported rotatively within the sleeve, primary and secondary windings wound on the core of the armature, a distributor rotor fitted concentrically to one end of the armature, 10 a brush on the distributor rotor associated with the secondary windings, a distributor stator mounted concentrically with the sleeve, collectors in the distributor stator arranged in the path of the brush, a 15 contact breaker fitted to one end of the armature, and a condenser located at the opposite end of the armature and associated with the primary winding on the armature.

18. A magneto of the rotary armature type having a body casting provided with field magnets and fixed pole pieces, an oscillatable sleeve of non-magnetic material passing through the body casting, means for retaining the sleeve within the body casting, 20 auxiliary pole pieces in the sleeve magnetically associated with the pole pieces in the body casting, a bearing in one end of the sleeve, a cover on the opposite end of the sleeve, a bearing in the cover, an armature having end shafts rotatably supported 25 in the bearings, a distributor rotor fitted concentrically on the armature, a distributor stator disposed concentrically on the cover, a plurality of collectors arranged symmetrically around the axis of the distributor 30 stator, a contact breaker located within the distributor stator, a condenser in the said armature, and a timing lever on the sleeve. 35

19. A magneto of the rotary armature type comprising a body casting, a cylindrical chamber in the body casting, fixed pole pieces in the body casting extending through the sides of the chamber, field magnets on the body casting in contact with the pole pieces, an oscillatable sleeve of non-magnetic material passing through and having its ends projecting beyond the cylindrical chamber in the body casting, an enlarged extension on one projecting end of the sleeve, a removable retaining ring on the opposite 40 projecting end of the sleeve, auxiliary pole pieces in the sleeve, a cover on the enlarged extension of the sleeve, an armature rotatively supported in the sleeve, an axial core on the centre of the armature, radial jaws at the ends of the core, inductors in the jaws, annular discs on the core adjacent to the inductors, primary and secondary windings on the core, a distributor rotor on the armature and located concentrically 45 within the cover, a distributor stator on the cover and concentric with the rotor, a plurality of collectors arranged symmetrically around the axis of the distributor stator, a contact breaker on the armature located within the cover on the sleeve, a timing lever on the sleeve, a condenser housing in the armature, and a condenser in the 50 said housing.

In testimony whereof I affix my signature. 55
